CLAIM

The ornamental design for a core for a cylinder lock, as shown and described.

DESCRIPTION

FIG. 1 is rear view of a core for a cylinder lock showing my new design;

FIG. 2 is a top view thereof;

FIG. 3 is a side view thereof, the cylinder lock core appearing the same when viewed from the opposite side; and,

FIG. 4 is a bottom view thereof.

The appearance of my new design as seen from the front forms no part of the claimed design.

The broken lines are shown for illustrative purposes only and for no part of the claimed design.
